UNITED STATES PATENT OFFICE.

LOUIS G. MASSICOTTE, OF PROVIDENCE, RHODE ISLAND.

SEALING-TAPE HOLDER AND MOISTENER.

Application filed August 10, 1922. Serial No. 580,895.

To all whom it may concern:

Be it known that I, LOUIS G. MASSICOTTE, a citizen of the United States, residing at Providence, in the county of Providence and State of Rhode Island, have invented certain new and useful Improvements in Sealing-Tape Holders and Moisteners, of which the following is a specification.

This invention relates to improvements in the construction of sealing-tape holders and moisteners, and has for its object to provide a holder of this character constructed substantially of banjo-shape for supporting a roll of gummed tape and adapted to serve as a water reservoir and to work with its roll of tape in a horizontal plane.

A further object of the invention is to provide a frictional means for supporting a tape roll above the plane of the body in a manner supplying the required friction to the rotating tape roll.

A still further object of the invention is to provide a spring for pressing the tape against the under side of the cutter plate for the purpose of more nearly centralizing the operating position of the tape and to facilitate threading the tape under the cutter and thus render more perfect the severing action of the cutter when the tape is drawn or torn across its edge.

The invention further consists in the provision of means for protecting the exposed surface of the roll while mounted upon its support.

With these and other objects in view, the invention consists of certain novel features of construction, as will be more fully described, and particularly pointed out in the appended claims.

In the accompanying drawings:

Figure 1 is a front or plan view of the sealing tape holder and moistener showing the roll of tape in dotted lines with its end led through the guides and over the moistening roll.

Figure 2 is a central sectional side elevation of my improved tape holder and moistener.

Figure 3 is an end view showing a portion of the base and the angular guide over which the tape is drawn to impart a one-quarter turn to the tape as drawn thereover also showing the open end guide finger under which the tape is led.

Figure 4 is a side elevation partly in section showing the spring as pressing the tape up against the under side of the cutting plate.

Figure 5 is a detail perspective view of the presser spring.

It is found in practice of advantage to provide a sealing-tape holder and moistener which is adapted to support the tape roll in a horizontal plane to minimize the room taken up when in working position upon a counter; also to permit the use of the roll of tape of a maximum diameter and that without danger of being in the way or tipping over; also to provide a spring guide finger to facilitate threading the tape under the knife plate and also to hold the tape against the under side of the knife blade to prevent a lateral slipping movement on the knife blade when applying a sideways or tearing movement to the tape, and the following is a detailed description of one means by which these advantageous results may be accomplished:

With reference to the drawings, 10 designates the body of the holder member which is preferably formed somewhat in the shape of a banjo, the same comprising an enlarged circular body portion 11 having a cooperating elongated radially-extending member 12, both the body and the extending arm portion being hollow as shown in Figure 2, and being provided with a bottom wall 14 and a top wall 13, the side walls 15 thereof providing a reservoir in which may be carried a large quantity of water for the purpose of moistening the tape, in the manner presently described, but obviously the arm portion alone may be employed as a reservoir if desired.

The bottom wall 14 is preferably provided with three rubber bosses 16 on which the holder may stand on a polished surface without injuring the same.

Near the outer end of this hollow arm, I have removed a portion of the upper wall 100 forming an opening 17 in which the moistening roll 18 is rotatably mounted, the side walls of the holder being grooved out as at 19 in this open portion, to serve as bearings for the roll shaft 20.

This moistening roll is provided with a roughened surface so that the water in the reservoir will adhere thereto and bring up

a sufficient quantity to properly moisten the gummed surface of the tape when presented thereto.

The enlarged or body portion of this holder is preferably provided with an up-standing spindle 21 which is threaded into a boss 22 in the middle portion thereof, which spindle is adapted to extend through a center hole in the roll of tape 23, to 5 rotatably support the same thereon and in order to provide a proper resistance to the rotation of this roll, I have formed a rib 23 extending across the body portion on which the side of the roll lies, the width 10 of the rib being designed to just supply the necessary friction to properly retard the rotation of the roll when the tape is being drawn therefrom.

In practice this roll of tape is designed 20 to lie flat upon the face of the holder and the holder is designed to lie in a horizontal position upon the table or counter, the gummed face of the tape lying outwardly.

It is, therefore, found necessary to impart 25 a one-quarter turn to the tape as drawn from the roll so that the gummed surface will be turned downwardly to contact with the face of the moistening roll. To effect this one-quarter turn, I have provided a 30 wire standard 24 fixed to the face of the holder, its outer portion being looped around forwardly as at 25 see Figure 1, and from this forward portion a part 26 of the wire extends downwardly at an angle 35 of substantially 45° , to rest upon the face of the holder and forward of this bar is positioned a transversely-extending guide finger 27 which is raised above the plane 40 of the holder-face and secured at one end on the boss 28 by a screw 29, the opposite end being free to permit the bight or loop of the tape to be passed thereunder.

Forwardly of this guide finger, I have 45 provided a transverse rib 30 on the arm of the holder, which serves to lift the gummed surface of the tape from the broad surface of the holder so as to permit a circulation of air thereunder and so prevent it adhering to the surface of the holder.

Forwardly of this rib 30, I have positioned a transverse plate or blade 31 which is secured at both ends to the bosses 32 by screws 33, the forward edge of this plate being beveled to a knife edge as at 34 so as 50 to facilitate the cutting or tearing of the tape when drawn across this edge to be severed.

It is found in some instances of some difficulty to thread the end of the tape quickly 55 beneath this knife plate and also to prevent the tape from slipping sidewise beneath the knife during the sidewise tearing action which results in a diagonal cut instead of one straight across, which is preferred.

To obviate this difficulty, I have provided

a flat spring 35 having an arm 36 connected at one end through a hole 37 to the screw 33, the opposite end 38 being free and this arm is arranged to extend along beneath the cutter plate 31.

The spring is also provided with a rearwardly extending arm 39 having a downwardly-turned end 40 to bear against the surface of the holder, whereby in threading the end of the tape beneath the cutter plate 70 it is only necessary to lay its end upon the spring arm 30 and then by pressing downwardly and forwardly the spring is slightly separated from the under side of the plate and at the same time the tape slides along the upper face of the spring beneath the cutter plate and over the roll 18, then when released this spring will lift the tape and bind it in position against the under side of the cutter plate thereby preventing the tape from slipping sidewise beneath the cutter plate when the tape is being torn over the edge thereof.

It is also found in practice that where 90 the roll of tape lies horizontally for some considerable time and is exposed to the moisture of the atmosphere and the moisture due to contact with the hand of the operator, of advantage to cover this face of the roll and so protect it against these deteriorating effects, and to accomplish this in a very simple and effective way, I have provided a disc or plate 41 having a central hole to fit over the spindle 21 and lay flat against the upper face of the tape roll to turn with it and when the roll is exhausted the plate is removed and subsequently placed over the face of the next fresh roll positioned in the holder.

My improved sealing tape holder and moistener is extremely simple and practical in construction, effective in its operation and by its use the tape may be readily fed forwardly until it becomes thoroughly moistened upon being passed over the moistening roll and by being held while severed, the tearing is quickly and accurately effected squarely across the cutter plate and the machine may be very rapidly operated.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A machine of the character described comprising a hollow body having a cooperating radially-extending hollow arm forming a water reservoir, said arm having an opening through its upper wall near its outer end, a moistening roll mounted in said opening, a center spindle in said body on

which the roll of gummed tape is rotatably mounted to lie in a plane parallel with that of the face of the body, a guide for leading the tape with a quarter turn to said moistening roll, and a cutter edge adjacent the roll.

2. A sealing tape holder and moistener comprising a hollow body having a narrow elongated cooperating radially extending member, the whole being adapted to work in a horizontal plane and said member being adapted to serve as a water reservoir, a moistening roll mounted in said extension, a tape roll receiving spindle in said body for supporting the tape above the plane of the reservoir, and an angular tape guide for imparting a one-quarter turn to the tape to be led over said roll.

3. A sealing tape holder and moistener comprising a tape carrying base of substantially banjo shape adapted to serve as a water reservoir and work in a horizontal plane, a tape moistening roll in the arm of said base, a center spindle on the body of said base to support the tape roll in a plane parallel with that of its base, guides on the arm portion for turning the gummed face of the tape downwardly and conducting the same over said roll when drawn outwardly, and a tape cutter plate near the edge of the roll.

4. A sealing tape holder and moistener comprising a tape-carrying base of substantially banjo shape adapted to serve as a water reservoir and work in a horizontal plane, a tape-moistening roll in the arm of said base, a center spindle on the body of said base to support the tape roll in a plane parallel with that of its base, a raised portion on the base on which the tape roll sets of a width to apply the required friction to said rotation of the roll, an angular tape guide for imparting a one-quarter turn to the tape when led thereover to turn its gummed surface downwardly, and a tape cutting guide plate adjacent said moistening roll.

5. A sealing tape machine comprising a hollow body having a narrow elongated cooperating radially extending member, the whole being adapted to work in a horizontal plane and said member serving as a water reservoir, a moistening roll mounted in said extension, a tape roll receiving spindle in said body, an angular tape guide for imparting to the tape a one-quarter turn as drawn thereover, a cutter plate serving as a guide to lead the tape over the said roll, and a spring for pressing the tape against the under surface of said cutter plate.

6. A sealing tape machine comprising a tape carrying base of substantially banjo shape adapted to serve as a water reservoir and work in a horizontal plane, a tape moistening roll in the arm of said base, a center spindle on the body of said base, guides on the arm portion for turning the gummed face of the tape downwardly and conducting the same over said roll when drawn outwardly, a tape cutter plate near the edge of the roll, and a flat spring located beneath the cutter plate and between which and the cutter plate the tape is led to facilitate the severing action of the cutter.

7. A sealing tape machine comprising a hollow body having a narrow elongated cooperating radially extending member, the whole being adapted to work in a horizontal plane and serve as a water reservoir, a moistening roll mounted in said extension, a tape roll-receiving spindle in said body, an angular tape guide for imparting to the tape a one-quarter turn as drawn thereover, a cutter plate serving as a guide to lead the tape over said roll, a spring for pressing the tape against the under surface of said cutter plate, and a longitudinally extending arm on said spring over which the tape is led to facilitate threading the tape beneath the cutter blade.

In testimony whereof I affix my signature.

LOUIS G. MASSICOTTE.
